CLAIM

We claim the ornamental design for a switch mount, as shown and described.

DESCRIPTION

FIG. 1 is a top-right perspective view of the switch mount;

FIG. 2 is a top view thereof;

FIG. 3 is a left side view thereof;

FIG. 4 is a front view thereof;

FIG. 5 is a right side view thereof;

FIG. 6 is a rear view thereof; and,

FIG. 7 is a bottom view thereof.

The dashed lines in various figures are for illustrative purposes only and form no part of the claimed design.
